Patented Feb. 8, 1927.

UNITED STATES PATENT OFFICE.

LAURENCE E. TOPHAM, OF WENHAM, MASSACHUSETTS, ASSIGNOR TO UNITED SHOE MACHINERY CORPORATION, OF PATERSON, NEW JERSEY, A CORPORATION OF NEW JERSEY.

SHOE-SUPPORTING-JACK MECHANISM.

Original application filed December 31, 1918, Serial No. 269,076. Divided and this application filed January 21, 1922, Serial No. 530,813. Renewed November 6, 1926.

The invention relates to shoe supporting jack mechanisms for machines for operating on shoes.

The jacking of a shoe which has been placed upon a jack by the operator may involve adjustment of the shoe either laterally or longitudinally, or both laterally and longitudinally, into a definite position on the jack and the clamping or securing of the shoe in adjusted position, or it may involve merely the clamping or securing of the shoe to the jack, depending upon the character of the jack, the character of the machine in which it is to be incorporated, and the character of the operation which is to be performed on the shoe.

One object of the invention is to relieve the operator of the greater part of the labor and of the careful and skilled attention which might otherwise be required in jacking the shoe, and to this end power operated mechanism is provided which, when thrown into operation, acts to automatically jack a lasted shoe placed upon the jack.

In applying the feature of automatic jacking to a jack which forms a part of an automatic machine requiring the shoe to be located in a definite position longitudinally of the jack, mechanism is provided which acts automatically when thrown into operation to thus locate the shoe. The provision of such mechanism forms a feature of the invention which is not confined in its application to jacks in which the other operations involved in jacking the shoe are automatically effected and which may be utilized with jacks in which some or all of such other operations are either manually or automatically performed.

In applying the feature of automatic jacking to a jack which is movable to transfer the point of operation along a shoe carried by the jack, mechanism is provided which acts automatically when thrown into operation to clamp the shoe on the jack, and the provision of mechanism for thus clamping the shoe on a jack which is thus movable forms in itself a feature of the invention.

The invention also contemplates the provision of mechanisms by which the un-jacking of the shoe after the completion of an operation thereon will be automatic, as well

as the restoration of the parts to their initial position ready for the reception of another shoe.

With a jack embodying the features outlined above the operator is relieved of the labor required in jacking and un-jacking the shoe, the rapidity of the jacking and un-jacking is increased and the location of the shoe in a predetermined position on the jack is insured with the exercise of practically no skill or care on the part of the operator.

The features above indicated, as well as various other novel features hereinafter described and specified in the claims, will be clearly understood from the accompanying drawings illustrating a preferred form of the invention, and the following detailed description of the constructions therein shown.

In the drawings Figure 1 is a view illustrating the jack in front elevation and the devices at the lower end of the jack spindle in section taken substantially on the line 1-1 of Fig. 2; Fig. 2 is a detail sectional view illustrating the devices at the lower end of the jack spindle taken substantially on the line 2-2 of Fig. 3; Fig. 3 is a sectional view taken substantially on the line 3-3 of Fig. 2; Fig. 4 is a view in vertical section of the jack; Fig. 5 is a view partly in vertical section and partly in front elevation of the jack illustrating certain of the parts in different positions from the position in which they are shown in Fig. 4; Fig. 6 is a detail view in vertical section illustrating a portion of the jack with certain of the parts in different positions from those in which they are shown in Figs. 4 and 5; Fig. 7 is a sectional view taken substantially on the line 7-7 of Fig. 5; Fig. 8 is a sectional view taken substantially on the line 8-8 of Fig. 5; Fig. 9 is a view in front elevation partly in section of a portion of the jack illustrating the parts in substantially the same positions as shown in Fig. 5; Fig. 10 is a view in front elevation of the portion of the jack shown in Fig. 9 with certain of the parts in different positions; Fig. 11 is a sectional view taken substantially on the line 7-7 of Fig. 5; Fig. 12 is a view similar to Fig. 10 illustrating certain of the parts in different positions; Fig. 13 is a view in side elevation of the portion of the jack shown in Figs. 9, 10 and 11; Fig.

- 13 is a sectional view taken substantially on the line 13—13 of Fig. 11; Fig. 14 is a detail view partly in side elevation and partly in section taken substantially on the line 5 14—14 of Fig. 4; and Fig. 15 is a detail view of a portion of the jack mechanism illustrating certain of the parts in different positions from those in which they are shown in Figs. 4 and 5.
- 10 The jack illustrated in the drawing comprises a heel support 1 and a toe rest 2 mounted upon a spindle 3. The jack is carried by a support 15 which may be mounted for movement in substantially the same manner as the rod support 53 of the machine illustrated and described in application Serial No. 269,076, filed December 31, 1918, of which the present application is a division. The jack spindle is connected with the support 15 so that the jack can rotate about the axis of the spindle and so that the jack can tip in any direction in substantially the same manner as the jack of the machine illustrated and described in said application.
- 15 25 The lower end of the jack spindle is secured to a hemispherical shell or casing 4 pivoted to swing upon bearing pins 5 (Figs. 1, 2 and 3) secured in a gimbal ring 6 and having their inner ends engaging in bearings in the shell. The gimbal ring 6 in turn is pivoted to swing upon bearing pins 7 mounted in the ring and having their outer ends engaging in bearings in a jack supporting wheel 8. The common axis of the bearing pins 5 is preferably located substantially at right angles to the common axis of the bearing pins 7 so that the shell 4 and the jack spindle can swing in any direction about its connections with the wheel 8. The wheel 8 is mounted to rotate on a vertical hollow stud or sleeve 9 which is secured by a clamp to the forward ends of the arms of the support 15, a ball bearing being interposed between the sleeve 9 and the wheel 8 to enable the wheel to turn with a minimum of friction. This manner of mounting the wheel 8 enables the jack spindle to be rotated freely.
- 20 30 35 40 45 50 55 60 65 The jack spindle may have substantially the same movements imparted thereto as the jack spindle of the machine illustrated and described in the application referred to above. As fully described in said application the jack spindle is rotated through substantially half a revolution in the direction indicated by the arrow α , Fig. 4, during the operation on the shoe. After the completion of the operation on the shoe and the disengagement of the shoe from the operating means, the jack is turned through substantially half a revolution in the direction indicated by the arrow β , Fig. 5, to restore the jack to starting position. In the illustrated construction these rotary movements of the jack may be produced by rotating the

wheel 8 by means of a cable 10 passing about the same.

The jack illustrated in the drawing is constructed and arranged so that upon the placing of the shoe on the jack the shoe is automatically located in a predetermined and unvarying position lengthwise of the jack regardless of the size of the shoe placed on the jack and is securely clamped in adjusted position, and that at the completion of the operation on a shoe, the shoe is unclamped and the parts of the jack are returned to their initial positions ready for the application of another shoe to the jack. The shoe is gaged with relation to the jack from the forward point in the bulge in the toe portion of the upper of the shoe. The toe rest 2 is concave in cross section so that it will center the toe of the shoe relative to the jack and is mounted on the upper end of an arm 11 on the jack frame. The heel support 1 consists of a last pin for insertion in the last pin hole in the last and is mounted on a lever 12 pivoted on a stud 13 carried at the upper end of a swinging arm 14. The heel support carrying arm 14 is pivoted at its lower end to the central portion of the jack frame by means of a stud 16 so that the arm may be swung toward and from the toe rest supporting arm 11 to carry the last pin toward and from the toe rest. Before a shoe is placed on the jack the arm 14 is located in a position relatively remote from the arm 11 and upon the placing of the shoe on the last pin 1 is swung toward the arm 11 to adjust the shoe in a predetermined position longitudinally of the jack. The arm 14 is acted upon by a comparatively heavy coiled spring 17 secured at one end to the arm 11 and at the other end to a pin 18 mounted in the outer end of a lever 20 pivoted upon a stud 22 secured in the arm 14. Upon the hub of the lever 20 is formed a series of gear teeth meshing with the teeth of a gear segment 24 formed on the last pin 18 lever 12. The opposite ends of the pin 18 are engaged in slots 26 in the arm 14 which limit the movement of the lever 20. When a shoe is applied to the jack the arm 14 is held substantially in the position shown in Fig. 5 relative to the arm 11 with the last pin located so that when the shoe is applied thereto the toe of the shoe will be out of engagement with the toe rest as shown in said figure, the coiled spring 17 being disengaged and the pin 18 held in engagement with the inner ends of the slots 26. Upon the placing of the shoe on the last pin the arm 14 is released so that it is free to move under the action of the coiled spring 17. By the action of said coiled spring the arm 14 is swung toward the arm 11 thereby carrying the toe of the shoe into engagement with the surface of the toe rest and sliding the same along the toe rest toward the forward end

thereof. The surface of the toe rest with which the toe of the shoe is thus brought into contact is inclined upwardly with relation to the arc about which the toe of the shoe is swung, so that as the toe of the shoe slides along this surface it is lifted thereby swinging the last pin lever 12 about the stud 13 and also swinging the lever 20 about the stud 22 in a direction to carry the pin 18 away from the inner ends of the slots 26. Thus when the shoe is adjusted in the proper position on the jack and the swinging movement of the arm 14 ceases, the parts described will have assumed substantially the positions shown in Fig. 4, the coiled spring 17 not only acting on the arm 14 to maintain the shoe in its adjusted position longitudinally of the jack but also through its action on the lever 20 tending to tilt the lever 12 in a direction to depress the toe of the shoe and thereby clamp the shoe firmly on the jack.

In order that the shoe may be located accurately in a predetermined and definite position longitudinally of the jack, mechanism is provided for arresting the swinging movement of the heel support carrying arm 14 toward the arm 11 when the forward point of the bulge in the toe portion of the upper reaches a definite predetermined position longitudinally of the jack. The mechanism for thus arresting the movement of the arm 14 comprises a bar 28 pivotally connected at one end with the arm 14 and having its other end arranged to pass through an opening in the toe rest supporting arm 11. The bar 28 is formed on its lower side with a series of rack teeth meshing with the teeth of a pinion 30 secured to a stud 32 mounted in a bearing in the arm 11. (See Fig. 13.) The rack bar 28 is engaged upon its upper side by a guide roll 34 which holds the same up to the pinion 30. To the forward end of the stud 32 is secured a ratchet wheel 36 and a pawl 38 mounted on a stud 40 in the arm 11 is arranged to engage the teeth of the ratchet wheel. When the arm 14 is swung toward the arm 11 to adjust the shoe longitudinally of the jack the ratchet wheel 36 is rotated in a clockwise direction, Fig. 5, by the longitudinal movement of the rack bar 28 and the teeth of the ratchet wheel face in a direction such that the rotation of the wheel in a clockwise direction will be arrested when the pawl 38 is engaged therewith. The pawl is normally held out of engagement with the ratchet wheel during the movement of the arm 14 toward the arm 11 by means of a latch 41 pivoted at 42 on the arm 11 and formed with a projection arranged to engage the tail of the pawl, as shown in Fig. 10. The latch and the pawl are both acted upon by a coiled spring 44 interposed between an arm on the latch and

the tail of the pawl which tends to move the latch into position to engage the pawl and also to move the pawl into engagement with the ratchet wheel 36. The latch is actuated to release the pawl by means of a rod 46 mounted for longitudinal movement in guides in the arm 11 with its lower end engaging an arm on the latch. The upper end of the rod 46 is engaged by a lateral projection formed on the lower end of a feeler lever 48 pivoted at 50 in a central slot in the toe rest. The upper end of the feeler lever 48 is located in position to be engaged by the bulge in the toe portion of the upper of a shoe applied to the jack. As the shoe is moved forwardly on the jack by the swinging movement of the heel support carrying arm 14 under the influence of the coiled spring 17 the bulge at the toe portion of the upper of the shoe engages the upper end of the feeler lever 48 thereby swinging the feeler lever on its axis and actuating the rod 46 and the latch 41 to disengage the latch from the pawl 38. Upon its release by the latch the pawl is engaged with the ratchet wheel 36 thereby arresting the rotation of the ratchet wheel and the swinging movement of the arm 14. The swinging movement of the arm 14 to adjust the shoe longitudinally on the jack is thus positively arrested when the forward point in the bulge in the toe portion of the upper of the shoe reaches a predetermined position longitudinally of the jack. The shoe after its adjustment in the proper predetermined position is held securely clamped on the jack by the action of the coiled spring 17 on the lever 20 as explained above.

The mechanism for controlling the swinging movements of the heel support carrying arm 14 comprises a toggle lever consisting of two pivotally connected links 52 and 54, of which the link 52 is pivotally connected with the arm 14 and the link 54 is pivotally connected with a lever 56 pivoted on a stud 58 carried by the central portion of the jack frame. The relative angular movement of the members of the toggle lever in a direction to straighten the toggle is limited by means of a projection 60 formed on the member 52 of the toggle lever and arranged to engage an abutment or contact face on the member 54 of the lever. A toggle actuating and controlling lever 62 is pivoted on the stud 58 by the side of the lever 56 and carries an abutment screw 64 for engagement with a shoulder formed on the lever 56. The levers 56 and 62 are connected by means of a coiled spring 66 which normally maintains the lever 56 in position relative to the lever 62 with the shoulder formed thereon in contact with the abutment screw 64. The lever 62 carries a bevel gear segment 68 meshing with a bevel gear 70 secured to the upper end of a shaft 72 mount-

ed in bearings in the jack spindle 3. Upon the lower end of the shaft 72 is formed a yoke 74, (see Figs. 1, 2 and 3) which embraces a gimbal ring 76 and is pivotally connected with the ring by means of bearing pins 78 secured in the ring and engaging in bearings in the arms of the yoke. The ring 76 embraces a yoke 80 mounted on the upper end of a stud 82 passing through and secured in the sleeve 9 and is pivotally connected with the latter yoke by means of bearing pins 84 secured in the ring and engaging in bearings in the arms of the yoke. The shaft 72 through its connection with the sleeve 9 is held from rotary movement with the jack spindle but is free to swing in any direction relative to the stud in accordance with the swinging movements of the spindle. When the shoe is placed on the jack 20 the toggle lever 52—54 is straightened and the toggle actuating and controlling lever 62 and the intermediate lever 56 are held in position through the engagement of the gear segment 68 with the bevel gear 70 to maintain the heel support carrying arm 14 in a position remote from the toe rest supporting arm 11 as shown in Fig. 5 against the tension of the spring 17. Upon the placing 30 of a shoe on the jack the toggle lever 52—54 is broken allowing the spring 17 to actuate the arm 14 to adjust the shoe in a predetermined position longitudinally of the jack and to clamp the same in position as shown in Fig. 4. As the jack is turned through substantially half a revolution in the direction of the arrow *a*, Fig. 4, during the operation on the shoe, the toggle actuating and controlling lever 62 is swung on the stud 58 in the direction of the arrow applied thereto in said figure and the intermediate lever 56 is swung therewith until at the completion of the operation on the shoe the toggle lever is straightened. As the jack is turned in the opposite direction or in the direction of the arrow *b*, Fig. 5, through substantially half a revolution after the completion of the operation on the shoe to bring the jack to its initial or starting position, the lever 62 is swung on the stud 58 in the direction of the arrow applied thereto in Fig. 5. The toggle lever 52—54 is then in a straightened condition and is moved longitudinally from the lever 62 through the lever 56 to swing the arm 14 away from the arm 11 into the position shown in said figure. The shoe is thus unclamped from the jack and may be removed from the jack merely by lifting the shoe from the last pin 1.

To take up lost motion and assist in straightening the toggle lever at the completion of the turning movement of the jack produced during the operation of the machine on the shoe a coiled spring 86 is attached at one end to the arm 14 and at its other end to a projection formed on the

member 52 of the toggle lever. This spring ensures the straightening of the toggle lever. The yielding connection between the intermediate lever 56 and the toggle actuating and controlling lever 62 will take care of any additional movement or overthrow of the lever 62 at the completion of the operation on the shoe after the toggle lever is straightened. During such additional movement of the lever 62 the lever 56 is held stationary by the toggle lever and the lever 62 moves independently of the lever 56. Fig. 15 shows the condition of the parts resulting from such additional movement of the lever 62.

During the sewing of the seam along the shank of the shoe on the side of the shoe first sewn the jack is turned to a certain degree in the direction of the arrow *b*, Fig. 5. If the operator should start the machine while the toggle lever is straightened the movement of the lever 62 in the direction of the arrow, Fig. 5, which would be produced by this rotary movement of the jack would be liable to result in breakage of certain of the parts. In order to break the toggle lever when this rotary movement of the jack occurs in case the machine is started with the toggle lever straightened, a chain 88 is attached at one end to the projection on the member 52 of the toggle lever and at its other end to the lever 56.

In order to disengage the pawl 38 from the ratchet wheel 36 and to reset the pawl in position to be engaged and held by the latch 41, the rack bar 28 is formed with a projection 90 at its outer end arranged to engage a laterally projecting arm 92 formed on the pawl. As the heel support carrying arm 14 is swung from the position shown in Fig. 4 to the position shown in Fig. 5, and the bar 28 is thus moved longitudinally to the left to the position shown in the latter figure, the projection 90 on the bar engages the arm 92 on the pawl and moves the pawl to the position shown in Figs. 5 and 9. The pawl is held in the position shown in Figs. 5 and 9 until the arm 14 is released and starts to swing toward the toe rest supporting arm 11 under the influence of the coiled spring 17 when the projection 90 on the bar 28 is disengaged from the arm 92 on the pawl by the longitudinal movement of the bar to the right. The pawl is then caught by the latch and held until the latch is disengaged from the pawl by the movement of the feeler lever 48 produced by the engagement of the shoe therewith.

The devices for breaking the toggle lever 52—54 upon the placing of the shoe on the jack comprise a dog 94 pivoted upon a vertically movable block 96 and arranged to engage the laterally bent end of an arm 98 formed on the member 52 of the toggle lever. The dog 94 is acted upon by a coiled

spring 95 which normally maintains the same in the position shown in Fig. 6 relative to the block 96. The block 96 is secured to the lower end of a rod 100 mounted for longitudinal movement in guides in the lever 12. The rod 100 is acted upon by a coiled spring 102 surrounding the rod within a recess in the lever 12 and interposed between a washer resting on the lower face of the recess and a collar 104 mounted on the rod and held from longitudinal movement thereon by a pin 106. This pin through its engagement with the upper face of the recess in the lever 12 limits the upward movement of the rod. The parts are constructed and arranged so that when the rod 100 is in elevated position the upper end of the rod projects some distance above the body of the lever 12 alongside the last pin 1 and the dog 94 is located above the laterally bent end of the arm 98 in position to engage the same as shown in Fig. 6. Fig. 6 shows the condition of the parts before a shoe is applied to the jack. Upon the application of a shoe to the last pin and the seating of the last pin in the last pin hole in the last, the last engages the upper end of the rod 100 and depresses the same. During the downward movement of the rod 100 the dog 94 engages the end of the arm 98 and swings the same downwardly, thereby breaking the toggle lever 52-54 and allowing the arm 14 to be actuated by the spring 17 to adjust the shoe longitudinally of the jack and to clamp the same to the jack. As the toggle lever is straightened by the turning movement imparted to the jack during the operation of the machine on the shoe, the laterally bent end of the arm 98 is swung upwardly to a position outside of the lower end of the dog 94. As the arm 14 is swung away from the arm 11 by the turning movement imparted to the jack to bring the same to its initial or starting position, the end of the arm 98 engages the lower end of the dog 94 and swings the same slightly inwardly against the action of the coiled spring 95 as shown in Fig. 5. Upon the removal of the shoe from the last pin the rod 100 is elevated by the action of the spring 102 and the lower end of the dog 94 is swung outwardly by the action of the coiled spring 95 over the end of the arm 98 as shown in Fig. 6. The parts of the jack are thus restored to their initial positions ready for the reception of another shoe.

The movement of the heel support carrying arm 14 under the influence of the coiled spring 17 upon the release of the arm by the toggle lever 52-54 if unrestrained is liable to result in breakage of certain of the parts. A dash pot mechanism is therefore provided for retarding the movement of the arm. This dash pot mechanism is adapted to be fluid controlled and, briefly described, com-

prises a cylinder 108 secured at its lower end to the jack frame, a longitudinally movable bar 110 having rack teeth formed at its upper end which are held in mesh with the pinion 30 by a guide roll 111 engaging the bar, a piston 112 secured to the bar 110, and a valve 114 mounted in the piston. This valve is constructed to allow the controlling fluid to pass freely from above the piston to the space below the same as the piston is moved upwardly in the cylinder, and to retard the passage of the fluid from below the piston as the piston is moved downwardly in the cylinder. The manner in which this dash pot mechanism operates to retard the movement of the arm 14 will be obvious without further description.

The nature and object of the invention having been indicated and the preferred embodiment of the invention having been specifically described what is claimed is:

1. A shoe supporting jack mechanism having, in combination, a jack for supporting a lasted shoe, and power operated mechanism acting when thrown into operation to automatically jack a shoe placed on the jack.

2. A shoe supporting jack mechanism having, in combination, a jack for supporting a lasted shoe mounted for movement to present the shoe to an operating means, and power operated mechanism acting when thrown into operation to automatically jack a shoe placed on the jack.

3. A shoe supporting jack mechanism having, in combination, a jack for supporting a lasted shoe, and mechanism arranged to be thrown into operation by the placing of the shoe on the jack and acting automatically thereafter to jack the shoe.

4. A shoe supporting jack mechanism having, in combination, a jack for supporting a lasted shoe mounted for movement to present the shoe to an operating means, mechanism acting when thrown into operation to automatically clamp a lasted shoe placed on the jack, and mechanism acting during the movement of the jack to re-set said clamping mechanism.

5. A shoe supporting jack mechanism having, in combination, a jack for supporting a lasted shoe, and mechanism arranged to be thrown into operation by the placing of the shoe on the jack and acting automatically thereafter to clamp the shoe on the jack.

6. A shoe supporting jack mechanism having, in combination, a jack for supporting a lasted shoe, mechanism acting when thrown into operation to automatically jack a shoe placed on the jack, and means operating to re-set said mechanism during the movements given the jack before returning it to initial position.

7. A shoe supporting jack mechanism

having, in combination, a jack for supporting a lasted shoe, mechanism acting when thrown into operation to automatically jack a shoe placed on the jack, and mechanism 5 acting at the completion of an operation on the shoe to un-jack the shoe and restore the parts of the jack to initial position.

8. A shoe supporting jack mechanism having, in combination, a jack for supporting a lasted shoe, mechanism for automatically jacking a shoe placed on the jack, tripping means therefor, and mechanisms for setting the tripping means during the movement of the jack in one direction and 10 for un-jacking the shoe and setting the jacking mechanism during the movement of the jack in the opposite direction.

9. A shoe supporting jack mechanism having, in combination, a movable jack for 20 supporting a lasted shoe, a spring operated mechanism for effecting an operation in the jacking of the shoe placed on the jack, means operated by movement of the jack for setting and holding the spring, and means 25 for tripping the holding means.

10. A shoe supporting jack mechanism having, in combination, a jack for supporting a lasted shoe comprising relatively movable heel and toe supports, a spring tending 30 to move the supports toward each other, means operated by the movement of the jack to initial position after an operation on the shoe to separate and hold the supports 35 against the action of the spring, and means for tripping the holding means.

11. A shoe supporting jack mechanism having, in combination, devices for supporting a lasted shoe, and power operated mechanism arranged to act automatically 40 when thrown into operation to locate the shoe in a predetermined position longitudinally on the jack.

12. A shoe supporting jack mechanism having, in combination, devices for supporting a lasted shoe, and mechanism arranged 45 to be thrown into operation by the placing of the shoe on the jack and acting automatically thereafter to locate the shoe in a predetermined position on the jack.

13. A shoe supporting jack mechanism having, in combination, devices for supporting a lasted shoe mounted for movement to transfer the point of operation along the shoe, and mechanism arranged to act automatically 55 when thrown into operation to clamp the shoe on the jack.

14. A shoe supporting jack mechanism having, in combination, devices for supporting a lasted shoe, and mechanism arranged 60 to be thrown into operation by the placing of the shoe on the jack and acting automatically thereafter to clamp the shoe on the jack.

15. A shoe supporting jack mechanism

having, in combination, devices for supporting a lasted shoe mounted for movement to transfer the point of operation along the shoe, means for clamping the shoe on the jack, and mechanism arranged to act automatically to unclamp the shoe after the 70 completion of an operation.

16. A shoe supporting jack mechanism having, in combination, devices for supporting a lasted shoe mounted for movement to carry the jack away from starting position 75 and to restore the jack to its starting position, means for clamping the shoe on the jack, and mechanism arranged to be thrown into operation by the movement imparted to the jack in restoring the same to starting 80 position and acting automatically to unclamp the shoe.

17. A shoe supporting jack mechanism having, in combination, devices for supporting a lasted shoe, means for adjusting 85 the shoe longitudinally on the jack, and automatically acting mechanism for restoring the adjusting means to its initial condition.

18. A shoe supporting jack mechanism having, in combination, devices for supporting a lasted shoe mounted for movement to carry the jack away from starting position and to restore the jack to its starting position, means for adjusting the shoe on the jack, and mechanism arranged to be thrown into operation by the movement imparted to the jack in restoring the same to starting 95 position and acting automatically to restore the adjusting means to its initial condition.

19. A shoe supporting jack mechanism having, in combination, devices for supporting a lasted shoe, and power operated mechanism arranged to act automatically to adjust the shoe in a predetermined position 100 longitudinally on the jack and to clamp the shoe in adjusted position.

20. A shoe supporting jack mechanism having, in combination, devices for supporting a lasted shoe, means for adjusting the shoe longitudinally on the jack and for 110 clamping the shoe in adjusted position, and mechanism arranged to act automatically to unclamp the shoe and to restore the parts of the jack to their initial condition.

21. A shoe supporting jack mechanism 115 having, in combination, a tilting last pin and a toe rest, and mechanism for moving relatively the last pin and toe rest toward each other to adjust the shoe on the jack, for yieldingly tilting the last pin to force 120 the toe of the shoe downwardly against the toe rest and thereby clamp the shoe in adjusted position.

22. A shoe supporting jack mechanism having, in combination, devices for supporting a lasted shoe, a spring, mechanism arranged to be actuated by the spring to locate the shoe in a predetermined position on 125

the jack, means for holding the spring out of operation, and means for tripping said holding means.

23. A shoe supporting jack mechanism having, in combination, devices for supporting a lasted shoe, a spring, mechanism actuated by the spring to clamp the shoe in operating position on the jack, means for holding the spring out of operation, and means for tripping said holding means.

24. A shoe supporting jack mechanism having, in combination, a jack frame, a toe rest carried thereby, an arm pivoted to the jack frame, a lever pivotally mounted on the arm, a last pin carried by the lever, and a spring and connections operating to swing said arm toward the toe rest and thereby adjust the shoe on the jack, and tending to swing said lever in a direction to depress the toe of the shoe so as to clamp the shoe in adjusted position.

25. A shoe supporting jack mechanism having, in combination, a jack frame, a rigid arm thereon, a toe rest mounted on said arm, an arm pivoted to the jack frame, a lever pivotally mounted on the arm, a last pin carried by the lever, a second lever also pivoted on the latter arm, gearing connecting said levers, a spring connecting the latter lever with the toe rest carrying arm and acting through said levers to swing the pivoted arm toward the toe rest so as to adjust the shoe on the jack and tending to swing the first lever in a direction to depress the toe of the shoe so as to clamp the shoe on the jack.

26. A shoe supporting jack mechanism having, in combination, a movable support for a lasted shoe, a spring tending to move the support in one direction, a toggle arranged when in straightened condition to hold the support in position against the action of the spring, and means for breaking the toggle to allow the spring to act.

27. A shoe supporting jack mechanism having, in combination, a movable support for a lasted shoe, a spring tending to move the support in one direction, a toggle arranged when in straightened condition to hold said support in position against the action of the spring, and devices operated by the placing of the shoe on the jack for breaking the toggle to allow the spring to act.

28. A shoe supporting jack mechanism having, in combination, a movable support for a lasted shoe, a spring tending to move the support in one direction, a toggle arranged when in straightened condition to hold the support in position against the action of the spring, means for breaking the toggle and means for straightening the toggle and for then actuating the same to carry the support back to its initial position.

29. A shoe supporting jack mechanism

having, in combination, a movable support for a lasted shoe, a spring tending to move said support in one direction, a toggle arranged when in straightened condition to hold said support in position against the action of the spring, means for breaking the toggle, and gearing operating during the movement imparted to the jack in an operation on the shoe to straighten the toggle and during the movement imparted to the jack in restoring the same to starting position to actuate the toggle to move said support back to its initial position.

30. A shoe supporting jack mechanism having, in combination, a movable support for a lasted shoe, a spring tending to move said support in one direction, a lever pivoted on the jack frame, a toggle connecting the lever with the support and arranged when in a straightened condition to hold the support in position against the action of the spring, means for breaking the toggle to allow the spring to act, and gearing operating during the turning movement imparted to the jack in an operation on the shoe to swing said lever in one direction and thereby straighten the toggle and during the turning movement imparted to the jack in restoring the same to starting position to swing said lever in the opposite direction and thereby actuate the toggle to move the support back to its initial position.

31. A shoe supporting jack mechanism having, in combination, devices for supporting a lasted shoe, mounted for movement to carry the jack away from starting position and to restore the jack to its starting position, mechanism arranged to act automatically when thrown into operation to clamp the shoe on the jack, and means operating to set said mechanism during the movement imparted to the jack in restoring the same to starting position after the completion of an operation on the shoe.

32. A shoe supporting jack mechanism having, in combination, devices for supporting a lasted shoe, mounted for movement to carry the jack away from starting position and to restore the jack to its starting position, mechanism arranged to act automatically when thrown into operation to locate the shoe in a predetermined position on the jack, and means operating to set said mechanism during the movement imparted to the jack in restoring the same to starting position after the completion of an operation on the shoe.

33. A shoe supporting jack mechanism having, in combination, a movable support for a lasted shoe, a slide connected with said support, a rotatable shaft, gearing connecting the shaft and the slide, a ratchet wheel mounted on the shaft, a pawl for engaging the ratchet wheel normally held out of engagement therewith, and means for throw-

- ing the pawl into engagement with the ratchet wheel to stop the rotation of the ratchet wheel and the movement of the slide and the support when the shoe is brought to 5 a predetermined position relative to the jack.
34. A shoe supporting jack mechanism having, in combination, a movable support for a lasted shoe, a slide connected with said support, a rotatable shaft, gearing connecting the shaft and the slide, a ratchet wheel mounted on a shaft, a pawl for engagement with the ratchet wheel, a feeler arranged to be engaged by the toe of the shoe, and connections between the feeler and the pawl for holding the pawl out of engagement with the ratchet wheel when the toe of the shoe is located out of contact with the feeler and for causing the pawl to be thrown into engagement with the ratchet wheel to stop the rotation thereof and the movement of the slide and the support when the shoe is located in a predetermined position on the jack.
35. A shoe supporting jack mechanism having, in combination, devices for supporting a lasted shoe, mechanism operable to adjust the shoe on the jack and to clamp the same in adjusted position, and a single spring for actuating said mechanism both to adjust and clamp the shoe.
36. A shoe supporting jack mechanism having, in combination, a shoe supporting jack provided with a spindle, a rotatable jack support, and a gimbal joint connecting the support and the spindle.
37. A shoe supporting jack provided with a spindle, a jack support movable transversely of the spindle axis and a universal joint between the support and the spindle.
38. A shoe supporting jack provided with a spindle, a jack support at the lower end of the spindle movable transversely of the spindle axis, and a universal joint between the end of the spindle and the support.
39. A shoe supporting jack, a vertical spindle on the upper end of which the jack is carried, a universal joint at the lower end of the spindle and a support for the joint movable transversely of the spindle axis.
40. A shoe supporting jack provided with a hollow spindle, a jack support, a gimbal joint connecting the spindle and the support, a shaft within the spindle, a gimbal joint at the end of the shaft, and mechanism on the jack operated by relative rotation of the gimbal joints.
41. A shoe supporting jack provided with a hollow spindle, a rotary jack support, a gimbal joint between the support and the spindle, a shaft within the spindle, a gimbal joint at the end of the shaft, means for preventing rotation of the latter joint, and mechanism on the jack operated by rotation of the jack support.
42. A shoe supporting jack provided with a hollow spindle, a shaft within the spindle, mechanism operated from the shaft for unjacking the shoe, and gimbal joints at the lower end of the spindle and shaft respectively mounted for relative rotation.
43. A shoe supporting jack provided with a spindle, a gimbal joint at the lower end of the spindle, a concentric shaft mounted in the spindle, a concentric gimbal joint at the lower end of the shaft, means permitting rotation of one gimbal joint and preventing rotation of the other, and mechanism for unjacking the shoe operated from the shaft.
44. A shoe supporting jack mechanism having, in combination, a jack for supporting a lasted shoe comprising heel and toe supports, and power operated mechanism acting automatically when thrown into operation to move said supports relatively to clamp a shoe on the jack.
45. A shoe supporting jack having, in combination, a jack for supporting a lasted shoe comprising heel and toe supports, and power operated mechanism acting automatically when thrown into operation to move said supports relatively toward each other to locate the shoe longitudinally on the jack and to move said supports relatively to clamp the shoe on the jack.
46. A shoe supporting jack mechanism having, in combination, a tilting last pin, a toe rest, and power operated mechanism operating automatically when thrown into operation to move relatively the last pin and toe rest to adjust the shoe longitudinally on the jack and clamp the shoe in position.
47. A shoe supporting jack mechanism having, in combination, a jack for supporting a lasted shoe comprising heel and toe supports, mechanism arranged to be thrown into operation by the placing of a shoe on the jack for relatively actuating the supports to clamp the shoe on the jack.
48. A shoe supporting jack mechanism having, in combination, devices for supporting a lasted shoe, and mechanism thrown into operation by the placing of the shoe on the jack for adjusting the shoe in a predetermined position longitudinally on the jack and for clamping the shoe in adjusted position.
49. A shoe supporting jack mechanism having, in combination, a jack for supporting a lasted shoe mounted for movement to present the shoe to an operating means, mechanism acting when thrown into operation to automatically clamp a lasted shoe placed on the jack, and mechanism acting automatically to reset said clamping mechanism.
50. A shoe supporting jack mechanism having, in combination, a jack for supporting a lasted shoe, power operated mechanism

acting when thrown into operation to automatically jack a shoe placed on the jack, and mechanism acting automatically to un-jack the shoe.

51. A shoe supporting jack mechanism having, in combination, devices for supporting a lasted shoe, power operated mechanism

acting automatically when thrown into operation to adjust the shoe longitudinally on the jack and clamp the shoe in adjusted position, and mechanism acting automatically to unclamp the shoe and restore the parts of the jack to their initial position. ¹⁰
